Primary Examiner — Philip S Hyder*(74) Attorney, Agent, or Firm* — Fitch, Even, Tabin & Flannery LLP(57) **CLAIM**

We claim the ornamental design for a mallet, as shown and described.

DESCRIPTION

FIG. 1 is a front and left side perspective view of a mallet in accordance with a first embodiment of my new design; FIG. 2 is a rear and left side perspective view thereof; FIG. 3 is a left side elevational view thereof, the right side elevational view being a mirror image thereof;

FIG. 4 is a front elevational view thereof;

FIG. 5 is a rear elevational view thereof;

FIG. 6 is a top plan view thereof; and,

FIG. 7 is a bottom plan view thereof.

The broken lines of the mallet represent environmental structure and do not form a part of the claimed design.
